tion, New York, N. Y., a corporation of New
York

Application December 29, 1948, Serial No. 68,018

3 Claims. (Cl. 250—27)

1

This invention relates to trigger circuits and more particularly to novel trigger circuits including arrangements for keying inherently binary triggers employing two grid controlled tubes, each tube having its plate coupled to a grid of the other tube.

In the prior art various circuit arrangements are provided to effect a keying of such triggers. One arrangement provides for the simultaneous application of keying pulses to commonly connected grids of the trigger tubes. Another arrangement provides extra tubes in parallel with the trigger tubes and connects a corresponding electrode of each extra tube together and to a common source of keying pulses. Each of these arrangements is disadvantageous in that feedback is applied to the trigger so as to oppose the switching action of the trigger. Consequently when high-speed keying of the trigger is attempted, the feedback effects predominate and the trigger is thereby rendered non-responsive.

Another arrangement of the prior art involves connecting the plate resistors of the trigger tubes together and to the plate supply voltage through a common resistor. The keying pulses are applied to the common juncture of the resistors. This arrangement is disadvantageous in that a large keying pulse is required because of the low impedance of the common resistor.

Another arrangement involves connecting the grid bias resistors of the tubes together and to a source of bias voltage through a common resistor. The keying pulses are applied to the common juncture of the resistors. This arrangement is disadvantageous in that extremely stable supply voltage is necessary to proper trigger operation as well as careful adjustment of circuit parameters.

Accordingly it is a principal object of the invention to provide a novel circuit arrangement for keying triggers wherein the above disadvantages are eliminated as practical problems limiting trigger operation.

Another object is to provide a trigger circuit responsive to keying pulses having a separation in time which does not exceed the time required for the trigger to switch completely from either stable condition to the other.

Another object is to provide a trigger operable over an extremely wide range of keying speeds.

Another object is to provide a trigger operable over an extremely wide variation in the supply voltage and amplitude of keying pulses.

Another object is to provide an inherently binary trigger circuit switchable to either stable

2

condition in response to a change in the value of the impedance in series with the plates or cathodes of the trigger tubes.

A further object is to provide a trigger circuit operable from a single voltage supply wherein the cathode of the trigger tubes are connected through at least one grid controlled tube to its source of voltage supply.

A further object is to provide a novel trigger circuit having the cathodes of its trigger tubes connected through a grid controlled tube to the cathode supply voltage and its plate circuit connected through a grid controlled tube to the plate voltage supply, said trigger circuit being responsive to the simultaneous or successive application of keying pulses from one or two sources.

A still further object is to provide a trigger circuit having the cathodes of the trigger tubes connected to its voltage supply through two parallel connected impedances, the value of at least one impedance being changed to switch the trigger from either stable condition to the other.

A still further object is to provide an inherently binary trigger including a plurality of keying circuits wherein each keying circuit is operably independent of and isolated from the other.

Generally, the invention includes a novel binary trigger circuit using two grid controlled tubes and having two stable conditions alternately assumed.

Keying circuits are inter-connected with the trigger tubes so that the trigger is switched in response to pulses from one keying circuit. Each keying circuit includes at least one grid controlled tube connected between either the commonly joined cathodes of the trigger tubes and the source of cathode voltage supply or connected between the plate circuit of the trigger tubes and the source of plate voltage supply. Switching of the trigger from one or two keying pulse sources is accomplished by applying the pulses to a single keying circuit connected in series with the cathodes of the trigger tubes. Also, switching of the triggers is obtained by applying the respective keying pulses to a keying circuit connected in series with the cathodes of the trigger tubes and to a keying circuit in series with the plate circuit of the trigger. The keying arrangements described herein are operable in response to the negative going front of a peaked, sine wave or rectangular pulses of low amplitude.

In order to simplify the description, these keying pulses are referred to hereinafter as merely keying pulses. The novel triggers permit a variation of several hundred per cent in the supply voltage

and are operable at much higher keying speeds than those of the prior art.

Other objects of the invention will be pointed out in the following description and claims and illustrated in the accompanying drawings, which disclose, by way of example, the principle of the invention and the best mode, which has been contemplated of applying that principle.

In the drawings:

Fig. 1 is a circuit diagram of a trigger circuit employing a keying circuit in series with the cathodes of the trigger tubes.

Fig. 2 is a circuit diagram of a trigger circuit employing a keying circuit in the plate and cathode circuits of the trigger tubes.

Fig. 3 is a circuit diagram of a trigger circuit employing a keying circuit using a single multi-grid tube to effect keying from two sources.

Fig. 4 is a circuit diagram of another embodiment utilizing principles illustrated by Fig. 1.

Fig. 5 is a circuit diagram showing a modification of the embodiment shown in Fig. 4.

Fig. 6 is a circuit diagram of another embodiment showing triode tubes connected in series with the cathodes of the trigger tubes to form the keying circuit.

Fig. 7 is a circuit diagram showing a modification of the embodiment shown in Fig. 6 wherein both the cathode and grid circuits of the trigger tubes are terminated in the keying circuit.

Referring more particularly to the drawings, each trigger circuit includes a 6SN7 type tube A. Each tube A includes two triode sections, A1 and A2 referred to herein as triodes A1 and A2. While the 6SN7 type tube has two tubes in a single envelope it is understood that the triodes A1 and A2 may be of the type where only one triode is in an envelope. The two stable conditions of the triggers are referred to herein as "on" and "off."

The "on" condition is assumed when the right-hand triode A2 is conductive and the left-hand triode A1 is non-conductive. The "off" condition is assumed when the right-hand triode A2 is non-conductive and the left-hand triode A1 is conductive.

The dot at the left of the trigger tube A indicates that the triode A1 is assumed to be initially conductive and that the trigger is "off." This is merely for the purpose of facilitating the explanation throughout the several figures.

The arrangement and operation of the trigger circuits will be described with reference to the values of applied voltage and the values of resistances and capacitances employed therein. These values are given solely for the purpose of clarifying the explanation and it is to be specifically understood that they may be varied considerably without departing from the principles of the invention.

Referring more particularly to Fig. 1 the trigger circuit includes the trigger tube A and a keying circuit including the 6SN7 type tube B having triode tube sections B1 and B2 referred to herein as triodes B1 and B2. The cathodes of the triodes A1 and A2 are connected together and through a potentiometer 10 to the commonly connected plates of the triodes B1 and B2. The plate of the triode A1 is connected through a resistor 11 of 10,000 ohms to a +250 volt line 12 and the plate of the triode A2 is connected through a resistor 13 of 10,000 ohms to the +250 volt line 12. The plate of the triode A1 is connected through a lead 14 and through a resistor 15 of 100,000 ohms and a capacitor 16 of 0.00005

microfarad, in parallel, to the control grid of the triode A2. The lower end of the resistor 15 is connected through a resistor 17 of 100,000 ohms to a zero volt line 18. Likewise, the plate of the triode A2 is connected through a lead 19 and through a resistor 20 of 100,000 ohms and a capacitor 21 of 0.00005 microfarad, in parallel, to the control grid of the triode A1. The lower end of the resistor 20 is connected through a resistor 22 of 100,000 ohms to the zero volt line 18. The cathodes of the triodes B1 and B2 are connected directly to the zero volt line 18. Resistors 23 and 24, each of 10,000 ohms, are connected from the control grids of the triodes B1 and B2 respectively to the zero volt line 18. Keying terminals 25 and 26 are connected through capacitors 27 and 28 respectively, each of 0.00005 microfarad, to the control grids of the triodes B1 and B2.

20 The control grids of the triodes B1 and B2 are normally at zero bias and both triodes are therefore highly conductive. Hence, a keying pulse applied to the control grid of either triode will reduce conduction through that triode.

25 The keying pulses, when applied to one of the triodes B1 and B2, effect sufficient reduction of current flow through that triode to initiate a switching of the trigger from either stable condition to the other. Hence, the trigger may be keyed by either the successive or simultaneous application of keying pulses to the terminals 25 and 26.

30 Since the keying pulses employed have a relatively low amplitude, such as for example 2 or 3 volts, positive pulses of corresponding amplitude are quenched and do not sufficiently effect the current flow through either triode B1 or B2 to switch the trigger.

35 When a negative pulse is applied to one of the terminals 25 or 26 the current flow through the corresponding triode B1 or B2 is decreased and the voltage at the cathodes of the triodes A1 and A2 correspondingly increased. This increase of voltage at the cathodes is equivalent to impressing a negative bias on the control grid of the triode A1 since the trigger is "off." This increase of voltage causes a decreased voltage drop across the plate resistor 11. The resulting positive voltage at the plate of A1 is transferred through lead 14 and the parallel connected resistor 15 and capacitor 16 to the control grid of triode A2 to render that triode conductive. As a result the voltage drop across plate resistor 13 is increased, the resulting negative voltage being transferred over the lead 19 and the parallel connected resistor 20 and capacitor 21 to the control grid of the triode A1 to render it still less conductive. The increased positive voltage at the plate of triode A1 is again transferred to the control grid of the triode A2 to render the latter still more conductive. This cumulative trigger action is continued until the triode A2 is rendered uniformly conductive and the triode A1 is rendered non-conductive to switch the trigger "on."

40 The next keying pulse applied to the terminals 25 and 26 or to either of them causes a similar increased voltage at the cathodes of the triodes A1 and A2. This increased voltage results in an increased positive voltage at the plate of the triode A2 and a transfer thereof through the lead 19 and the parallel connected resistor 20 and capacitor 21 to the control grid of the triode A1. The resulting negative voltage at the plate of the triode A1 is transferred over the lead 14 and the parallel connected resistor 15 and capaci-

tor 16 to the control grid of the triode A2 to render A2 still less conductive. The resulting positive voltage at the plate of the triode A2 is again transferred to the control grid of the triode A1 to render it still more conductive. This cumulative trigger action is continued until the triode A1 is rendered uniformly conductive and the triode A2 is rendered non-conductive to switch the trigger "off."

It is seen that the small keying pulses applied to either terminal 25 or 26 cause a relatively large voltage change at the cathodes of the tube A because of the amplification provided by the tube B. Potentiometer 10 is provided to adjust the potential of the cathodes of the trigger tube A so that when either of the triodes A1 or A2 conducts its grid bias is substantially zero. Obviously, the potentiometer 10 may be replaced by a fixed load if the keying pulses are of substantially constant amplitude.

Referring to Fig. 2 the voltage supply to operate the trigger circuit is supplied between a +400 volt line 30 and a zero volt line 31. The values of resistors 32, 33 and 34 are 20,000 ohms, 200,000 ohms, and 200,000 ohms respectively, and the values of resistors 35, 36 and 37 are 20,000 ohms, 200,000 ohms, and 200,000 ohms respectively. The capacitors 38 and 39 each have a value of 0.0001 microfarad. The triode B1 has its cathode connected to the commonly connected plate resistors 32 and 35 and its plate connected to the +400 volt line 30. The control grid of triode B1 is connected through resistor 40 of 150,000 ohms to the line 30. The commonly connected cathodes of tube A are connected through the potentiometer 10 to the plate of the triode B2 and the cathode of B2 is connected through a potentiometer 41 to the zero volt line 31. It is seen that this circuit arrangement and the components employed are similar to those employed in Fig. 1 except for the differences noted above.

The triodes B1 and B2 are normally highly conductive. A keying pulse applied to the terminal 26 decreases the conduction through the triode B2 and causes a switching of the trigger in the manner described in connection with Fig. 1.

A keying pulse applied to the terminal 25 causes decreased conduction through the triode B1 and a corresponding increase in the voltage drop across it. As a result the voltage at the control grid of the conducting triode A1 is decreased and causes an increased voltage to appear at its plate. This increased voltage is transferred to the control grid of the non-conducting triode A2 to initiate conduction through it. The resulting decreased voltage at the plate of triode A2 is then transferred to the control grid of triode A1 to further decrease conduction through A1. This cumulative trigger action is continued until the triode A1 is non-conductive and the triode A2 is uniformly conductive to switch the trigger "on."

The next keying pulse applied to the terminal 25 causes a similar decrease in the voltage at the control grid of the triode A2 and initiates the cumulative trigger action which finally switches the trigger "off."

The circuit of Fig. 2 retains all of the advantages of that of Fig. 1. An additional advantage of the circuit of Fig. 2 is that potentiometer 41 may be adjusted to operate the triode B2 as either an amplifier or a cathode follower in order that the potential of the cathodes of the trigger tube A will vary linearly with a change in the voltage between the lines 18 and 12. The ad-

justment of potentiometer 41 will change the bias on the triode B2 and therefore permit keying in response to positive or negative keying pulses without changing or adjusting the circuit arrangement associated with the trigger tube A.

Referring to Fig. 3 the keying circuit includes a 6AS6 pentode type tube C. The plate of tube C is connected directly to the commonly connected cathodes of the trigger tube A, but it is understood that a plate load may be provided for the purposes stated in connection with the potentiometer 10 of Fig. 1. The screen grid of the tube C is connected to the +250 volt line 12 through a resistor 42 of such value that 100 volts is impressed on the screen grid. A by-pass capacitor 43 is also connected to the screen grid and is of such value that the bias voltage supplied through the resistor 42 to the screen grid will be held at a substantially constant value.

20 The control grid of the tube C is connected through the capacitor 27 to the keying terminal 25 and the suppressor grid is connected through the capacitor 28 to the keying terminal 26. It is obvious from the circuit arrangement that the bias on the control grid and suppressor grid is zero and that the bias on the screen grid is positive, hence tube C is highly conductive. A keying pulse applied to the terminal 25 or 26 will place a negative bias on the corresponding grid of the tube C and will therefore decrease the conduction through the tube C and place an increased voltage on the cathodes of the triodes A1 and A2. This increased voltage will cause a switching of the trigger as described in connection with Fig. 1. Since the application of a keying pulse to either the control or suppressor grid of tube C results in a switching of the trigger it is clear that the trigger is responsive to the simultaneous and successive application of keying pulses to terminals 25 and 26. This circuit illustrates one way to switch a trigger from two sources with a keying circuit including only one tube while retaining the advantages of the circuits of Figs. 1 and 2.

Referring to Fig. 4 there is shown substantially the circuit arrangement of Fig. 1. In this embodiment only triode B2 is utilized and its cathode is connected through the potentiometer 41 to the line 18 and capacitors 44 and 45 each having a value of 0.000056 microfarad. This circuit arrangement illustrates one way of switching a trigger, in accordance with the principles of the invention, in response to pulses from a single keying source.

Referring to Fig. 5 there is shown a circuit arrangement substantially as in Fig. 4 except that the plate of the triode B1 is connected directly to the cathodes of the trigger tube A and its cathode is connected directly to the zero volt line 18. In addition, germanium crystal rectifiers G are connected between the control grid of triode B1 and the line 18. These rectifiers are provided to insure that positive pulses irrespective of their amplitude will be ineffective to switch the trigger circuit. These rectifiers eliminate any possibility of a switching of the trigger in response to positive keying pulses of high amplitude because of the low impedance path provided by the rectifiers between the control grid of the triode B1 and the line 18.

Referring to Fig. 6 there is shown a modification of the circuit arrangement of Fig. 1. The plate of the triode B2 is connected directly to the cathodes of the trigger tube A. The cathode of the triode B2 is connected to the plate of the

triode **B1** and the control grid of **B2** is connected through the resistor **24** to the cathode of **B2**. The cathode of triode **B1** is connected directly to the zero volt line **18**.

Triodes **B1** and **B2** are normally highly conductive and since they are connected in series, a change in the conduction through one triode causes a similar change in the conduction through the other triode. Hence the application of keying pulses to either or both of the terminals **25** and **26** causes a decrease in the conduction through the triodes **B1** and **B2** and a corresponding increase in the voltage at the cathodes of the trigger tube **A** causes a switching of the trigger in the manner described in connection with Fig. 1.

The use of the triodes **B1** and **B2** connected in series is particularly advantageous over their use in parallel as illustrated in Fig. 1. When connected in parallel one triode, due to its conduction when keying pulses are applied successively to the triode, tends to prevent a change in voltage at the cathodes of the trigger tube **A** and thereby tends to decrease the effect of the keyed triode on the voltage at those cathodes. But when the triodes are connected in series the voltage change caused by either triode is transferred to the cathodes of the tube **A** without any decreased effect being caused by the other triode. This is because the conduction through either triode **B1** or **B2** in Fig. 6 controls conduction through the other.

Referring to Fig. 7 there is shown a circuit arrangement similar to that of Fig. 6 except that the lower end of the resistors **22** and **17** terminate at the commonly connected plate of triode **B1** and cathode of triode **B2**.

The trigger circuits of Fig. 1 through Fig. 7 inclusive, in addition to the advantages pointed out above, find particular utility where a trigger is required having a very fast period of response. The triggers of the invention will switch from either stable condition to the other in response to keying pulses having a separation in time which does not exceed or is even less than the time required for the trigger to switch completely from either stable condition to the other. The trigger characteristic which permits a subsequent switching of the trigger before it has switched completely to a stable condition in response to the last keying pulse is attributed to the avoidance of feedback effects through the novel keying arrangement.

While there have been shown and described and pointed out the fundamental novel features of the invention as applied to preferred embodiments, it will be understood that various omissions and substitutions and changes in the form and details of the triggers illustrated and in their operation may be made by those skilled in the art, without departing from the spirit of the invention. It is the intention, therefore, to be limited only as indicated by the scope of the following claims.

What is claimed is:

1. A trigger circuit including two cross-connected triode vacuum tubes and having two stable conditions alternately assumed during each of which a different one of said tubes is conductive, the cathodes of said tubes being commonly connected together and the plates of said tubes being connected together through resistors; a high and a low voltage line; first and second sources of keying pulses; first and second grid controlled keying tubes normally conductive, said first keying tube having its cathode connected to said

resistors and its plate connected to said high voltage line; a first potentiometer connected between the cathodes of said vacuum tubes and the plate of said second keying tube; a second potentiometer connected between the cathode of said second keying tube and said low voltage line, said first and second potentiometers permitting operation of said second keying tube as an amplifier or a cathode follower; means for applying keying pulses from said first source to the control grid of said first keying tube to decrease the voltage at the control grid of the conducting vacuum tube to initiate a switching of the trigger to the other stable condition and means for applying keying pulses from said second source to the control grid of said vacuum tubes to initiate a switching of the triggers to the other stable condition.

2. A trigger circuit including two cross-connected grid controlled vacuum tubes and having two stable conditions alternately assumed during each of which a different one of said tubes is conductive and non-conductive respectively; a conductive connection only between the cathodes of said tubes; a high and a low voltage line; a plate resistor connected between the respective plates of said tubes and said high voltage line; a source of pulses for effecting a switching of the trigger from either stable condition to the other; only a variable impedance, normally at a low value, connected between said conductive connection and said low voltage line; means for applying pulses from said source to said variable impedance to automatically adjust said impedance to a higher value to increase the voltage at the cathode of each of said vacuum tubes to cause a switching of the trigger from either stable condition to the other; a potentiometer connected between said variable impedance and said conductive connection to adjust the voltage change at the cathodes of said vacuum tubes when the impedance is adjusted from said low value to said higher value.

3. The trigger circuit set forth in claim 2 wherein a potentiometer is connected between said variable impedance and said low voltage line to provide for controllable adjustment of the change in the value of said impedance in response to said pulses.
